DISHWASHING TRAY FOR CUPS

Ralph Ettlinger, Jr., 1370 Lincoln Ave. S.,
Highland Park, Ill.

Filed May 5, 1960, Ser. No. 60,456

Term of patent 14 years

(Cl. D49—1)

Fig. 5

FIGURE 1 is a top plan view of the dishwashing tray for cups embodying my new design;

FIGURE 2 is a side view thereof;

FIGURE 3 is a cross-sectional fragmentary side view thereof taken across the lines 3—3 of FIGURE 1;

FIGURE 4 is a cross-sectional fragmentary view thereof taken across the line 4—4 of FIGURE 1; and

FIGURE 5 is an enlarged perspective view of the upper right hand corner of FIGURE 1.

The side and ends not shown are substantially like the side shown in FIGURE 2.

I claim:

The ornamental design for a dishwashing tray for cups, as shown and described.
